ATTORNEY

UNITED STATES PATENT OFFICE

LAWRENCE LANGNER, OF NEW YORK, N. Y., ASSIGNOR TO THE LONGSIGN CORPORATION, OF DAYTON, OHIO, A CORPORATION OF OHIO

ELECTRIC SIGN

Application filed July 30, 1928. Serial No. 296,155.

This invention relates to electric signs for producing traveling words or other visual indications.

One object of the invention is the provision of an electric sign having a series of illuminated lamps and a traveling tape having perforations so coordinated with the lamp arrangement as to register with the lamps to form traveling characters which move across the sign.

Another object of the invention is the provision of an electric sign of the character mentioned in which the lamps are all arranged in a definite regular arrangement, and in which a ground glass screen is provided in front of the perforated tape to produce distinct indications or characters which however are without objectionable glare.

Other objects and advantages of the invention will be apparent from the following description and from the accompanying drawings in which—

Fig. 1 is a top plan view of a sign embodying the present invention;

Fig. 2 is a front elevation of the sign, parts of which are broken away to more clearly show the lamps;

Fig. 3 is a detail sectional view on the line 3—3 of Fig. 2 showing the manner in which the perforations of the tape register with the lamps;

Fig. 4 is a portion of a modified form of construction, shown in front elevation; and

Fig. 5 is a transverse section on the line 5—5 of Fig. 4.

This invention pertains particularly to electric signs embodying a bank of illuminated lamps in front of which is a traveling perforated tape, the perforations of which produce moving words or other visual indications. As shown in the drawings, in which similar reference numerals designate like parts in the various views, the sign comprises a box or casing 10 in which is a bank or series

11 of electric light bulbs 12. These electric light bulbs are arranged in a definite regular relationship, being provided in vertical and horizontal rows as shown in Fig. 2. The light bulbs 12 are preferably of comparative-

of them may be arranged in each vertical row of the series. Each lamp has a screw-threaded terminal which is threaded into a metallic plate 13, and each is provided with a contact portion which abuts against a second metallic plate 14, these two metallic plates forming electrical conductors which supply electricity at suitable voltage to the lamps. The two plates 13 and 14 are electrically connected as indicated at 15 to a suitable transformer 16 which is provided in any suitable location, preferably within the box or casing 10.

In front of the series of lamps 11 is a moving tape 18. This tape is provided with suitable perforations 20, arranged to outline suitable letters or other characters, and these perforations are so arranged on the tape as to be coordinated with the regular positioning of the individual lamps. As shown in Fig. 3 each perforation in the tape is adapted to register in front of one of the lamps so that the light from such a lamp may pass unobstructed through the tape at this point.

And the various perforations move from registration with one lamp into registration with the next succeeding lamp as the tape travels from right to left. The result of this arrangement therefore is that the light shines through the perforations in the tape all the while the tape is moving across the sign, but when any perforation in the tape is in exact registration with a lamp a maximum amount of light passes through the perforation, and an indication is produced of very pleasing appearance, and one which is quite easy on the eyes and without objectionable flicker.

The variations in light intensity as any perforation passes from registration with one lamp to registration with a succeeding lamp is sufficient merely to attract the attention of a passer-by without objectionable optical effect. The tape 18 is preferably a flexible tape guided by the guide rollers 22, and moved by a drum roller 23 which is shown connected to a small electric motor 24 by means of a belt 25 so that the tape is driven from this drum roller at the proper speed, the direction of motion of the tape being from right to left to one viewing the sign so

that he can properly read the traveling words or indications.

The tape may be of any suitable opaque or semi-opaque material, and the perforations in the tape, although shown in the drawings as being approximately round, may be of other configuration to obtain a proper pleasing appearance. If desired the tape may be made of colored material, such as green, for example, so that the light which shines through the perforations seems to be viewed on a green background. Obviously the tape may be otherwise colored as desired.

In front of the perforated tape, the sign is preferably provided with a ground glass screen 27, which may if desired be suitably colored. Of course other material than glass may be used for this screen, but preferably the material is of a frosted or ground character so that there is some diffusion and blending of the light, giving the appearance of a continuous letter outline rather than a series of individual light spots, yet maintaining the outline of the character sufficiently so as to be easily read.

In the modification shown in Figs. 4 and 5 each lamp is enclosed on its sides by light colored or metallic shield surfaces 30 as shown, these shield surfaces being provided by a series of horizontal metallic strips which engage a similar vertical series in the well-known "egg-crate" manner, so that light from one lamp is not reflected out from another lamp, and each source of illumination is of a more individual nature. The employment of such a shield, however, is not necessary to the proper operation of the sign.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A sign comprising a series of lamps regularly arranged in a definite regular relationship in several horizontal rows and adapted to be illuminated all at the same time, and a perforated tape having perforations arranged in several horizontal rows adapted to register with the lamps to form traveling characters, and means for moving said tape in front of said lamps so each perforation registers with a large number of lamps as it moves across the sign.

2. A sign comprising a series of small electric lamps regularly arranged in several straight horizontal rows, an opaque tape having perforations adapted to register with the lamps to form traveling characters, and means for moving said tape in front of said lamps.

3. A sign comprising a series of lamps reg-

ularly arranged in vertical and horizontal rows and adapted to be illuminated all at the same time, a colored tape having perforations outlining characters, and means for moving said tape in front of said lamps to form traveling characters, the perforations in the tape being movable horizontally so as to register with successive lamps.

4. A sign comprising a series of lamps arranged in a definite regular relationship in several rows, and a perforated tape having perforations adapted to register with the lamps to form traveling characters, means for moving said tape in front of said lamps, and a ground glass screen in front of said tape.

In testimony whereof I hereto affix my signature.

LAWRENCE LANGNER.
